GEOCHEMICAL PROSPECTING

Edwin E. Roper, Tulsa, Okla., assignor to Standard Oil and Gas Company, Tulsa, Okla., a corporation of Delaware

Application July 30, 1942, Serial No. 452,842

7 Claims. (Cl. 23—232)

The present invention relates to a process for the location of mineral oil deposits which are beneath the ground and more particularly to a process for analyzing certain components to be found in the soil whereby it is possible to determine the approximate location of said subterranean petroliferous deposits.

It is known that the soil itself at or near the surface of the earth and also the air in this soil contains various substances which are indicative of the presence of petroliferous deposits below. Such indicator substances may be gaseous hydrocarbons, liquid hydrocarbons and solid or waxy hydrocarbons and other materials.

It is furthermore known that the quantity of the indicator substances is a measure of the probability of existence of a petroleum deposit below. These substances have been taken from the soil and also from the air in the soil and analyzed by various means to obtain a value which can be placed on a graph or map or other type of chart. When a series of such values have been obtained, the map or chart will exhibit certain characteristics which can be utilized for locating oil deposits.

Often the indicator substance is contained in the soil gases. By the term "soil gases" I intend to refer to both the air obtained from the interstices of the soil as well as the gases obtained by desorption of soil samples. The soil gases are treated in a purification train or the like so as to remove certain contaminating gases such as CO₂, water vapor and so forth, and the quantity of uncontaminated hydrocarbon gases is then measured to obtain a value which can be recorded as mentioned above.

It has been found, however, that the concentration of apparent hydrocarbon gases derived from a single sample of soil gas varies over a period of time, decreasing at first comparatively rapidly and then more slowly. For example, in one instance a value of 90 parts per million of apparent hydrocarbon was obtained when the gas was analyzed immediately after the desorption from the soil sample. The same gas, after standing for a period of about 90 hours, gave a value of only 14 parts per million. The exact cause or reason for this decrease in apparent hydrocarbon content is not too clear but it is believed, for example when the soil samples are desorbed by heating that slight pyrolytic decompositions occur and that certain spontaneous reactions may take place within the evolved gas during the ensuing period which decrease the measurable quantity or concentration of apparent hydrocarbons.

If the gases, after desorption, are permitted to stand for any length of time these reactions proceed and thereby affect the measurable apparent hydrocarbon content of the gas when it is analyzed.

I have found that a substantially constant value of true hydrocarbon concentration can be obtained by treating the apparent hydrocarbon gases, after desorption, with a strong oxidizing agent. While the gases may be treated very shortly after desorption, it is not essential that this step be carried out immediately thereafter for substantially constant values may be obtained even though the treating step is carried out some time after desorption. When the gases are so treated and subsequently analyzed for hydrocarbon concentration, a value is obtained which will be substantially constant whether the gases are analyzed immediately following the desorption and treatment with oxidizing agent or whether a period of several hours or days is permitted to elapse before the final analysis. It is believed that the treatment with the oxidizing agent removes from the gaseous mixture certain unstable or very reactive compounds, which, if permitted to remain in the gaseous mixture spontaneously react over a period of time. It has been noted that the values obtained by following the method of the present invention are in general substantially the same as those obtained by analyzing soil gases which have been permitted to stand for extended periods during which time the spontaneous reactions occur. It would seem that according to known processes the unstable compounds, which are formed by the desorption step, would increase the apparent value of the hydrocarbon concentration, whereas if the hydrocarbon mixture containing the unstable compounds is permitted to stand, the latter will react to form various compounds which would be removed from the hydrocarbon stream before the final analysis is made. When air obtained from the interstices of the soil is used as a prospecting method, substances are present which are stable but are not hydrocarbons; the method claimed in my invention removes these spurious substances and gives actual hydrocarbon values.

An object of the invention is to provide an improved process for analyzing soil gases obtained by desorption of soil samples to obtain more reliable information with minimum delay.

Another object of the invention is to provide an improved process for analyzing soil gases obtained from the interstices of soil samples.

Still another object of the present invention is

to provide an apparatus for carrying out the present process.

Other objects of the present invention will be apparent as the description thereof proceeds.

Particular reference is made to the drawings, forming a part of this specification in which,

Figure 1 shows a schematic flow sheet for removing the soil gases from a soil sample according to the present invention, and

Figure 2 shows a schematic flow sheet for analyzing the soil gases.

In Figure 1 the apparatus for removing the soil gases from a soil sample by desorption is shown. This apparatus is initially urged with purified nitrogen or other inert gas which is introduced through line 1. A pressure regulator 2 can be set to determine the rate of flow of the inert gas. After the system has been entirely purged, stopcock 3 is turned to establish communication between the water supply reservoir 4 and flask 5 (of known volume) and the stopcock 6 is turned to establish communication between the flask 5 and line 7. The flask 5 is then filled with water from reservoir 4. Stopcock 6 is then turned to establish communication between line 8 and flask 5. The inert gas is introduced through line 1 to trap 9 which is maintained at a temperature of from about -296° F. to about -320° F. by immersion for instance in liquid oxygen (B. P. -296° F.), liquid air (B. P. -306° F.), liquid nitrogen (B. P. -320° F.), or liquid nitrogen boiling under reduced pressure. The inert gas passes from trap 9 through line 8 to flask 5 displacing the water contained therein. This enables one to obtain a definite predetermined quantity of nitrogen to be used for assisting in removal of the hydrocarbon gases evolved from the soil sample. Subsequently, stopcock 6 is turned to establish communication between flask 5 and line 1. The inert gas in flask 5 is forced through line 7 by filling flask 5 with water from reservoir 4 and then through flow indicator 10 and line 11 into the tube 12, which is maintained at approximately 200° F. to 212° F. by means of a hot water bath or the like. The inert gas flowing upward through the tube 12 carries with it the evolved desorbed hydrocarbon gases as well as all other evolved gases which were originally present in the soil sample together with any gases formed by pyrolytic decomposition occurring in 12. The mixture of evolved gases and inert gas leaving the tube 12 passes through line 13 to a scrubber 14 which contains a strong oxidizing agent. The oxidizing agent may be in the form of an acid or alkaline solution, or in solid powder form. It has been found in this connection that KMnO₄ is particularly suitable for the purposes of the present invention but other oxidizing agents such as K₂Cr₂O₇ and the like may be used. If, for instance, a KOH-KMnO₄ solution is used in the scrubber, not only are the pyrolytic decomposition products modified but also the CO₂ present in the gas mixture is partially or entirely removed. It has been found that the KMnO₄ solution may have a concentration of from about 0.1 molal to about 0.01 molal whereas the KOH may be about 0.1 molal. Other concentrations may be used but these give satisfactory results. The purified gases pass through line 15 to flask 16 which has been filled previously with water or other inert liquid. When the water in flask 16 has been replaced by the soil gases, the flask is removed from the system shown in Figure 1 and connected to line 18 shown in Figure 2. At

all times during the desorption of the hydrocarbon gases from the soil sample, a slight excess pressure of inert gas is maintained in the system to avoid the possibility of contamination of the gas sample by atmospheric constituents.

Since the hydrocarbon gases in admixture with the inert gas have been partially freed from the contaminating gases through the treatment with the oxidizing agent, the flask 16, if properly sealed at its outlets, may be stored for any length of time or may be analyzed immediately. The flask 16 is connected to scrubber 19 (Figure 2) which in turn is connected to line 20. Line 20 leads into the purification train having sections 21 and 22. The whole system, shown in Figure 2 from 34 to 20, is evacuated to a low pressure, of about 0.1 micron or less. In order to equilibrate the purification train with gas of a concentration substantially the same as that subsequently to be analyzed, a certain amount, say 50 cc. to 500 cc., of the gaseous mixture in flask 16 is drawn through the purification train by means of a vacuum applied at 23 and thereby voided, stopcock 24 being closed during this step. At this point stopcock 25 is closed and stopcock 24 is opened whereby the required volume of the gas is drawn from flask 16 through line 18, scrubber 19, line 20, sections 21 and 22 of the purification train, into flask 26, the volume of flask 26 being known from a previous standardization. Stopcock 24 is then closed. Since the pressure within flask 26 can be measured by manometer 27, and since the ambient temperature is known, the volume of the moisture-free gas within flask 26, which is to be analyzed, may be computed. Section 21 of the purification train contains potassium hydroxide or the like for removing any carbon dioxide present in the gaseous mixture. Section 22 of the purification train contains phosphorous pentoxide or the like for removing the final traces of water vapor. As previously stated the strong oxidizing agent, such as potassium hydroxide-potassium permanganate solution contained in scrubber 19, will effectively remove many compounds which might be present in the gas mixture, such as nitrous oxide, aldehydes, ketones, carbonyl oxysulfide, alcohols, mercaptans, ketenes, acrolein, alkenes and alkynes and the like. A mercury cut-off 28, 29, 30 and 31 is provided so that thorough pre-evacuation can be performed when the mercury level is below the branch of the V, yet when it is above the branch of the V, all of the measured gas sample from flask 26 must pass through trap 32. By opening stopcock 25, with mercury levels at 29, the proper amount of the purified anhydrous gas sample in flask 26 is pumped rapidly through the trap 32 which is maintained at a temperature of from about -296° F. to about -320° F. or colder by refrigerating the same with liquid oxygen, liquid air or liquid nitrogen. Vacuum is available at all times by means of pumps not shown, connected to 34. This process is continued until the gage at 33 shows a pressure of about 200 microns (0.2 mm.) or less or until only about 0.1 percent of the original sample remains in flask 26. Stopcock 25 is then closed and the pumping continued until the condensed material in trap 32 shows a pressure of 0.1 micron or less. This procedure removes all oxygen, argon, nitrogen, carbon monoxide, helium, neon and the greater part of the ethane unless the trap 32 is cooled to -320° F. or colder, at which temperatures little ethane will remain gaseous. The cold trap 32, containing a glass wool plug, is

very efficient in its condensing action, it does not offer a great resistance to flow and yet retains any fog that may form. Upon reaching 0.1 micron the mercury level in the Y 29 is raised up the U tubes from 29 to marks 30 and 31 thereby confining the condensed material in trap 32 in a definite isolated volume. At this point the refrigerant about trap 32 is removed and the trap is allowed to warm to room temperature. This may be hastened, if desired, by placing a beaker of tap water about the trap. The condensed material in trap 32 vaporizes during this heating and the pressures exerted by these vapors are then ascertained on gage 33. A McLeod gage can be employed for gage 33 is desired. A few successive readings may be taken to give assurance that the vaporization is complete and the final pressure obtained from the gage is the pressure of the vaporized gas contained in the known, fixed volume 30, 32, 33 and 31.

The methods of calculating the hydrocarbon concentration when the above data have been obtained are well known and will not be discussed herein.

It is obvious that various modifications may be used in place of those devices shown in the drawings without departing from the spirit and scope of the present invention. It will be understood also that while the invention has been described with reference to a particular arrangement of apparatus, that this is not to be construed as a limitation but rather only as an example. The scope of the present invention is to be determined by the claims appended hereto.

What I claim is:

1. In a method of geochemical prospecting wherein soil gases are analyzed for significant hydrocarbon content as an indication of petrolierous deposits below the location from which the gases were obtained, said gases containing relatively unstable impurities which normally, over a period of time, decreasingly exaggerate the results of the subsequent analysis for significant hydrocarbon content, the steps of desorbing the gases from the soil, treating said gases, after removal from the soil but before analysis, with a strong oxidizing agent which is inert toward said significant hydrocarbons, said treatment being carried out under such conditions that said impurities are largely removed from the gases, the treated gases being protected pending analysis from contamination by other hydrocarbon containing gases, whereby the subsequently obtained analytical result will be more reliable.

2. In a method of geochemical prospecting wherein soil gases are analyzed for significant hydrocarbon content as an indication of petrolierous deposits below the location from which the gases were obtained, said gases containing relatively unstable impurities which normally, over a period of time, decreasingly exaggerate the results of the subsequent analysis for significant hydrocarbon content, the steps of desorbing the gases from the soil, treating said gases, after removal from the soil but before analysis, with an alkali metal oxidizing agent which is inert toward said significant hydrocarbons, said treatment being carried out under such conditions that said impurities are largely removed from the gases, the treated gases being protected pending analysis from contamination by other hydrocarbon-containing gases, whereby the subsequently obtained analytical result will be more reliable.

3. In a method of geochemical prospecting

wherein soil gases are analyzed for significant hydrocarbon content as an indication of petrolierous deposits below the location from which the gases were obtained, said gases containing relatively unstable impurities which normally, over a period of time, decreasingly exaggerate the results of the subsequent analysis for significant hydrocarbon content, the steps of desorbing the gases from the soil, treating said gases, after removal from the soil but before analysis, with KMnO₄, said treatment being carried out under such conditions that said impurities are largely removed from the gases, the treated gases being protected pending analysis from contamination by other hydrocarbon containing gases, whereby the subsequently obtained analytical result will be more reliable.

4. In a method of geochemical prospecting wherein soil gases are analyzed for significant hydrocarbon content as an indication of petrolierous deposits below the location from which the gases were obtained, said gases containing relatively unstable impurities which normally, over a period of time, decreasingly exaggerate the results of the subsequent analysis for significant hydrocarbon content, the steps of desorbing the gases from the soil, treating said gases, after removal from the soil but before analysis, with a KOH solution of KMnO₄, said treatment being carried out under such conditions that said impurities are largely removed from the gases, the treated gases being protected pending analysis from contamination by other hydrocarbon containing gases, whereby the subsequently obtained analytical result will be more reliable.

5. In a method of geochemical prospecting wherein soil gases are analyzed for significant hydrocarbon content as an indication of petrolierous deposits below the location from which the gases were obtained, said gases containing relatively unstable impurities which normally, over a period of time, decreasingly exaggerate the results of the subsequent analysis for significant hydrocarbon content, the steps of desorbing the gases from the soil, treating said gases, after removal from the soil but before analysis, with a KOH solution of KMnO₄, the concentration of the KOH in said solution being about 0.1 molal and the concentration of the KMnO₄ being from about 0.1 molal to about 0.01 molal, said treatment being carried out under such conditions that said impurities are largely removed from the gases, the treated gases being protected pending analysis from contamination by other hydrocarbon-containing gases, whereby the subsequently obtained analytical result will be more reliable.

6. A method of geochemical prospecting comprising the steps of obtaining soil samples from a plurality of spaced locations in the ground, desorbing the gases from the soil, said gases containing relatively unstable impurities which normally over a period of time decreasingly exaggerate the results of the subsequent analysis for significant hydrocarbon content, treating said gases, after removal from the soil but before analysis, with a strong oxidizing agent which is inert toward said significant hydrocarbons, said treatment being carried out under such conditions that said impurities are largely removed from the gases, protecting the treated gases pending analysis from contamination by other hydrocarbon-containing gases and analyzing the treated gases for significant hydrocarbon content for an indication of petrolierous deposits below the locations from which said soil samples were obtained.

7. A method of geochemical prospecting comprising the steps of obtaining soil samples from a plurality of spaced locations in the ground, desorbing the gases from the soil, said gases containing relatively unstable impurities which normally over a period of time decreasingly exaggerate the results of the subsequent analysis for significant hydrocarbon content, treating said gases, after removal from the soil but before analysis, with $KMnO_4$, said treatment being carried

10

out under such conditions that said impurities are largely removed from the gases, protecting the treated gases pending analysis from contamination by other hydrocarbon-containing gases and analyzing the treated gases for significant hydrocarbon content for an indication of petrolierous deposits below the locations from which said soil samples were obtained.

EDWIN E. ROPER.
